(57) **CLAIM**

The ornamental design for a notebook computer as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the notebook computer in the closed status;

FIG. 10 is another perspective view thereof showing the notebook computer in the closed status;

FIG. 11 is an enlarged view of the portion, labeled '11' of FIG. 1; and,

FIG. 12 is an enlarged view of the portion, labeled '12' of FIG. 2.

The even-dashed broken lines shown in the drawings illustrate portions of the notebook computer that form no part of the claimed design.

The long-dash short-dash broken lines define the boundaries of the claimed design and form no part thereof.

The additional set of broken lines showing detail boxes and lead lines in FIGS. 1-2 and 11-12 represent the extents of the enlarged detail views and form no part of the claimed design.
